UNITED STATES PATENT OFFICE.

JOSEPH F. MILLER, OF SACRAMENTO, CALIFORNIA.

CLAM-SHELL BUCKET.

1,111,719.

Specification of Letters Patent. Patented Sept. 22, 1914.

Application filed June 11, 1913. Serial No. 773,040.

To all whom it may concern:

Be it known that I, JOSEPH F. MILLER, a citizen of the United States, residing at Sacramento, in the county of Sacramento 5 and State of California, have invented new and useful Improvements in Clam-Shell Buckets, of which the following is a specification.

This invention relates to a clam shell 10 bucket.

It is the object of this invention to provide a clam shell bucket and means for operating same, whereby the jaws of the bucket will be caused to move to their closed position 15 when loading before being lifted.

A further object is to provide a cable operated mechanism for opening and closing clam shell buckets by which the closing and the elevating of the bucket will be effected 20 by a single cable, and in which the initial pull on the elevating cable will operate to close the jaws of the bucket before exerting an upward pull thereon.

Another object is to provide a mechanism 25 of the above character which is simple in construction and efficient in operation.

The invention primarily resides in providing the jaws of a clam shell bucket with upwardly-extending operating arms, the 30 arms of one jaw of the bucket crossing the arms of the other jaw when the bucket is in either its closed or open position, mounting pulley sheaves on the outer ends of said arms, reeving a hauling cable around 35 said sheaves and securing its end in such manner that an initial pull on the hauling cable will operate to close the jaws of the bucket, and as the jaws are closed will operate to lift the bucket.

40 The invention further consists of the parts and the construction and combination of parts as hereinafter more fully described and claimed, having reference to the accompanying drawings, in which—

45 Figure 1 is a side view of the invention showing the jaws of the bucket in their open position in full lines, and in their closed position in dotted lines. Fig. 2 is a section and elevation on the line $a-a$ of Fig. 1. Fig. 3 is a side elevation of a modified form of the invention, showing the

bucket in its closed position in full lines, and in its open position in dotted lines.

In the drawings A and B indicate the jaws of an ordinary clam shell bucket, on the 55 sides or ends of which arms 2 and 2' are rigidly mounted; the arms 2 and 2' being pivotally connected together at 3. The arms 2 and 2' are so shaped that when the jaws A and B of the bucket are in either their closed or open 60 position, the arms 2 and 2' will cross each other at or above their pivotal connection 3, so that an inward upward movement of the outer ends of the arms will cause the jaws A and B to move to their closed po- 65 sition.

Mounted on the outer ends of the arms 2 and 2' are sheaves 4, a pair of sheaves 4 being provided on each of the arms 2 and 2'.

In the form of the invention shown in 70 Figs. 1 and 2, the sheaves 4 are revolvably mounted on stud shafts 5, carried by the arms 2 and 2'; and in the form of the invention shown in Fig. 3, the sheaves 4 are mounted on stud shafts 5 supported on links 75 6, pivoted to the ends of the arms 2 and 2'. A hauling cable 7 leading from any suitable operating mechanism, not shown, and passing over a direction pulley 8 on a boom 9, is rove around the sheaves 4 on the 80 arms 2 and 2', and has its outer end rigidly secured to any suitable point.

In the form of the invention shown in Fig. 1, the hauling cable 7 passes around and under a direction roller 10, carried on 85 the outer ends of arms 11, pivoted on the shaft 5, on the arm 2; the hauling cable 7 being rove around the direction pulley 10 after passing over the direction roller 8, and before passing under the sheaves 4 on 90 the arm 2. The cable 7, after passing around the sheave on the arm 2', is rove around the sheave 4 on the arm 2, and thence back and forth around as many sheaves 4 as may be mounted on the arms 2 and 2', the 95 end of the cable 7 being secured at 12 to the outer end of an arm 2'.

As a means for preventing the direction pulley 10 and arms 11 from fouling the cable 7, the outer ends of the arms 11 are 100 connected to a yoke 13, attached to the end of a cable 14, passing upward and over

direction wheels 15 on the boom 9, and connected at its other end to a counter-weight 16. The weight 16 operates to normally exert an upward pull on the arms 11, thereby preventing the latter from dropping downward when the hauling cable 7 is slackened, thus keeping it from becoming entangled with the portion of the cable 7 extending between the outer ends of the 10 arms 2 and 2'.

In the form of the invention shown in Fig. 3, the direction pulley 10 is dispensed with; the hauling cable 7 passing under the sheave 4 on the arm 2, thence under and 15 around a sheave 4 on the arm 2', back, over and under a second sheave 4 on the arm 2, thence under and around a second sheave 4 on the arm 2', the outer end of the hauling cable 7 in this case being attached to the 20 boom 9.

Connecting with the jaws A and B, adjacent to their outer edges, are short cables 17 which connect at their outer ends to a ring 18. The ring 18 is secured to the end 25 of a cable 19 which passes over a direction wheel 20 on the boom 9, and leads to any suitable operating means.

Let it be assumed that the jaws A and B of the bucket are in their open position, as 30 shown in Fig. 1, and that a pull is exerted on the hauling cable 7 in the direction of the arrow b. The operation will then be as follows: The pull exerted on the cable 7 will be transmitted to the outer ends of the arms 35 2 and 2' in such direction as to move the arms 2 and 2' upward and toward each other, as indicated by the arrows c, on their pivotal connection 3; this movement of the arms 2 and 2' acting to advance the lower 40 edges of the jaws A and B toward each other, as indicated by the arrows d. The jaws A and B in advancing toward each other are caused to enter the earth shovel-fashion by reason of the weight of the 45 bucket being supported by the ground; the cable 19 being slackened during this operation. When the jaws A and B have closed together, further inward movement of the arms 2 and 2' will be prevented, so that a 50 continued pull on the cable 7 will operate to elevate the bucket with its load, the bucket being elevated by the cable 7 and moved to any suitable point of discharge by swinging the boom 9 in the usual manner. To open 55 the bucket, the releasing cable 19 is drawn taut and the hauling cable 7 is slackened. The pull of the cable 19 will operate to move the jaws A and B to their open position, thus discharging the contents of the bucket 60 and restoring the arms 2 and 2' to their normal extended position; the hauling cable 7 being let out to permit spreading movement of the arms 2 and 2'. The bucket will then be supported on the cable 19 and can be

lowered into contact with the earth by letting out the cables 19 and 7, simultaneously.

By crossing the arms of the jaws of the bucket and connecting their outer ends by means of a cable rove back and forth over sheaves carried by the arms, both jaws of the bucket will be closed simultaneously by a single cable; the pull exerted by the cable being distributed equally to both jaws of the bucket and in such manner as to force the jaws into the material being worked without exerting an upward or lifting pull thereon. This is advantageous in that it permits of the operation of the clam shell bucket on unloosened soil.

It is manifest that while I have shown a 80 pair of sheaves 4 on each arm 2 and 2', this number may be increased or diminished as occasion may require; a larger number being employed when a greater leverage is desired.

Having thus described my invention, what I claim and desire to secure by Letters Patent is:

1. In a clam shell bucket, a pair of jaws, operating means comprising pivotally connected arms, each jaw having a pair of arms rigidly connected thereto on opposite sides thereof, sheave carrying means for each jaw connected to each of the arms of the respective jaws, and a single combined hoisting and jaw closing cable secured at one end to a stationary point and being rove back and forth and around the sheaves and adapted to have its opposite end operated to draw the arms together to close the jaws of the 100 bucket.

2. In a clam shell bucket, a pair of jaws, an arm rigidly connected to each jaw, the arm of one jaw being pivoted to the arm of the other jaw, the arms crossing each other above said pivotal point, sheaves carried on the outer ends of the arms, a single hauling cable rigidly secured at one end to a stationary point and being rove around the sheaves and having its opposite ends adapted to be operated to draw the arms together to close the jaws, a direction roller engaged with the last named end of the cable, means to movably support the direction roller from one of said arms, and a counter-balanced cable having one end connected to said supporting means to hold same in an upright position out of engagement with said last named arm during the opening and closing movements of said arms.

3. In a clam shell bucket, a pair of jaws, an arm rigidly connected to each jaw, the arm of one jaw being pivoted to the arm of the other jaw, sheaves carried on the outer ends of the arms, a single hauling cable 125 rigidly secured at one end to a stationary point and being rove around the sheaves and having its opposite end adapted to be op-

erated to draw the arms together to close the jaws, means movably connected to the outer end of one arm for engagement with the last named end of the cable, and means to hold said means in an upright position during the opening and closing movements of the arms.

In testimony whereof I have hereunto set my hand in the presence of two subscribing witnesses.

JOSEPH F. MILLER.
